UNITED STATES PATENT OFFICE.

JESSE C. MOORE, OF INDIANAPOLIS, INDIANA, ASSIGNOR TO COLUMBIA SCHOOL SUPPLY COMPANY, OF INDIANAPOLIS, INDIANA, A CORPORATION.

DESIGN FOR A CHAIR-DESK.

57,369.

Specification for Design.

Patented Mar. 15, 1921.

Application filed August 23, 1920. Serial No. 405,522. Term of patent 7 years.

To all whom it may concern:

Be it known that I, JESSE C. MOORE, a citizen of the United States, residing in the city of Indianapolis, county of Marion and State of Indiana, whose post-office address is 1821 North Pennsylvania street, have invented a new, original, and ornamental Design for a Chair-Desk, of which the following is a specification, reference being had to the accompanying drawing, forming part thereof.

In the figure there is shown a perspective view of the chair desk, showing my new design.

I claim as my invention:

The ornamental design for a chair desk, substantially as shown.

JESSE C. MOORE.
